Fraser, Myers & Manley.

UNITED STATES PATENT OFFICE.

MEADE WILDRICK, OF SAVANNAH, GEORGIA, ASSIGNOR, BY MESNE ASSIGNMENTS, TO THE SESAMEE COMPANY, OF HARTFORD, CONNECTICUT, A CORPORATION OF CONNECTICUT.

LOCK.

Application filed February 15, 1926. Serial No. 88,364.

This invention relates to improvements in permutation locks, sometimes called combination locks, said improvements being of general application to locks of the type mentioned irrespective of their intended use, but herein disclosed for purposes of illustration in the form of a combined door latch and lock.

One of the novel features of the lock comprises a permutation mechanism to control the movements of a locking member, said mechanism including pairs of movement-obstructing elements of which one element of each pair is provided with a part which 5 obstructs lock-releasing movement of another of said elements except when one of the elements of each pair has been set in a predetermined position, the elements which cooperate with the settable elements being 10 shiftable to varying relative positions whereby the combination of the lock may be changed.

As herein disclosed, the settable movement-obstructing elements are rotatably 15 mounted in a casing or housing and have portions of their peripheries exposed for manipulation. The cooperating movement-obstructing elements are rotatably mounted upon an extension of the locking member in 20 concentric relation, and have heads whereby they may be shifted from one position to another to change the combination, means being provided to hold them in any position in which they are set.

35 A further object of the invention is to provide the locking member with an operating bar spanning the movement-obstructing elements of the permutation mechanism and connected with the opposite ends of the part 40 of the locking member surrounded thereby, said operating bar providing means whereby a manipulator may be disposed in any desired location in the housing and serve as a means through which the locking member 45 may be moved from effective to ineffective position, and vice versa, through the agency of an operating connection between the manipulator and the operating bar.

In the drawings illustrating the preferred 50 form of the invention,—

Figure 1 is a vertical section through a lock on the line 1—1 of Fig. 3 viewed in the direction indicated by the arrows, said lock having the above-described features of im-

provement applied thereto, the parts being 55 indicated in their normal positions, the locking member being shown in its holding position, and the settable movement-obstructing elements being represented in their "set" position, to permit free movement of the 60 locking member.

Fig. 2 is a similar sectional view of the lock, the locking member and associated parts having been moved to "release" position. 65

Fig. 3 is a vertical section through the lock on the line 3—3 of Fig. 1 viewed in the direction indicated by the arrows.

Fig. 4 is a horizontal section through the lock along the line 4—4 of Fig. 2 viewed in 70 the direction indicated by the arrows, the positions of the various parts being the same as those represented in Fig. 1.

Fig. 5 is a view in cross-section on the line 5—5 of Fig. 1 viewed in the direction 75 indicated by the arrows, said section being taken through a part of the locking member and the detachable connections between said member and the operating bar.

Fig. 6 is a perspective view of one of the 80 pairs of movement-obstructing elements, one of said elements being in the form of a dial wheel or permutation wheel, and the other in the form of a sleeve having a stop to co-operate with the dial wheel and an indicia-bearing head whereby it may be shifted to various positions. 85

Fig. 7 is a detail view of one end of one 90 of the permutation wheels, illustrating means whereby different positions in which it may be set may be ascertained independently of the use of visible markings and similar means whereby a definite position of reference may also be ascertained.

In the preferred form of the invention 95 herein disclosed it comprises a locking member in the form of a reciprocatable bolt or latch element 20, mounted in a casing or housing 21, and movable from a holding or effective position, illustrated in Fig. 1, to a releasing or ineffective position, illustrated in Fig. 2. To control the movements of the locking member a permutation mechanism is provided, comprising pairs of movement-obstructing elements of which one element of each pair may be mounted in the casing and the other on the locking member. It is important that these elements be so formed 100 105

that one has a part adapted to prevent lock-controlling movements of the other except when one of said elements is set in a predetermined position. The elements of each 5 pair may, if desired, be arranged in end-to-end relation with their axes in alignment.

In the preferred form herein disclosed, the pairs of movement-obstructing elements comprise settable permutation wheels 22 10 having peripheral portions extending through slots 23 in the casing whereby they may be set, and sleeves 24, 24', 24'' provided with stops or abutments 25 adapted to pass through slots 26 in the permutation wheels 15 when the wheels have been so set as to bring the slots in registration with the abutments.

The concentric sleeves 24, 24', 24'' may be rotatably mounted upon an extension 27 of the bolt or bar 28 to which the locking member 20 may be secured or of which it may form a part.

The permutation wheels may be supported upon, and journaled for rotation about, the sleeves 24, 24', 24'' respectively, and end- 25 wise movement of said wheels may be prevented by means of partitioning members 29, 30 which may form fixed parts of the casing. The locking member and parts connected therewith may be so mounted as to 30 move endwise in the casing through openings or guideways 31, 32, 33 located respectively in the end wall of the casing and in the partitions 29 and 30.

Each of the permutation wheels may be 35 provided with an extension 34 of cylindrical form, the inner diameter of which may be of a size sufficient to provide a clearance-way for the associated abutment 25 and permit free rotation of the wheel except when 40 the abutment has been moved into its slot 26. The outer surface of each extension 34 may serve as a drum or brake-wheel to operate with a brake-element 35 (Fig. 3), which may be secured to a neighboring part 45 of the casing by means of a screw or other appropriate fastening device 36. The extensions 34 and brake-elements 35 serve as means whereby the permutation wheels may be retained in the various positions in which 50 they may be set.

Suitable means may be provided whereby the locking element may be moved from its effective position, indicated in Fig. 1, to its ineffective position, indicated in Fig. 2, when 55 the permutation wheels have been so set as to bring the slots 26 in registration with the abutments 25. As herein disclosed, such operating means comprises a knob 37 journaled in the casing and having, as a part thereof, a pinion 38 in meshed relation with a rack 39 forming part of an operating bar 40 so disposed as to bridge or span the permutation wheels, and having its ends connected with the ends of the bolt structure 60 and associated parts which are surrounded

by said wheels. As illustrated in Figs. 1 to 4, inclusive, the operating bar is so disposed as to move lengthwise through openings 41, 42 in the partitions 29, 30. It is provided at one end with an angular attaching element 43 in which the sleeve 24'' is journaled. At its other end it is provided with an attaching element 44 which, for reasons to be hereinafter set forth, is detachably secured to the main part of the bar by a screw or other suitable fastening device 45 (Fig. 5) and to the bolt portion of the locking element 28 by a screw or other suitable fastening device 46.

If desired, a spring 47 may be provided, 80 normally tending to maintain the locking element in its holding or effective position and capable of returning it to such position when removed therefrom, if free to do so. This spring, as clearly indicated in Figs. 1, 85 2 and 3, may be confined between the partition 29 and the attaching element 44 of the operating bar.

The manipulator 37 may be held in its assembled relation in the casing by fastening means of any appropriate character, such, for example, as the ring 48 and screw 49 illustrated in Fig. 3.

The positions to which the permutation wheels must be moved in order to bring the slots 26 in registration with the abutments 25 may be varied, and the combination of the lock thereby changed, by shifting the relative positions of the sleeves 24, 24', 24'' and thereby varying the relative positions of the abutments. To facilitate the change of the combination in this manner, the sleeves may be provided with indicia-bearing heads 50, 50', 50'' whereby they may be independently rotated. If desired, the heads may be detachably, but non-rotatably, secured to their respective sleeves by means of lugs or keys 51 which may extend into slots or keyways 52 provided therefor in the heads, as best illustrated in Fig. 6. The 100 sleeve-shifting heads 50, 50', 50'' may be held in any of the various positions to which they may be shifted, by means of a catch or other suitable retaining element 53. This retaining element may be pivotally connected 105 with the angular attaching element 43 of the operating bar, as at 54, and may be swung about its pivotal connection with said element 43 to a position such as to release the sleeve-shifting heads and permit their movement to any desired position. The retaining element 53 and its mounting may be so constructed as to be maintained in effective position by the friction between the parts of the pivotal connection 54, or the retaining 110 element may be yieldingly held in effective position by a spring (not shown).

As a means of determining the various positions in which each of the permutation wheels may be set, the outer surface of its 115

extension 34 may be provided with a series of depressions 55 adapted to be yieldingly engaged by a head 56 on the end of the detent 35. In the form of the invention herein disclosed, the extension is provided with ten equally spaced depressions defining ten positions in which the permutation wheel may be set. If desired, the exposed peripheral portion of the permutation wheel may be divided into ten corresponding portions which may be differentiated by markings of any appropriate character, such as a zero (0) and the digits 1 to 9. Such markings afford visual means useful in setting the permutation wheel. These visual markings, however, may be dispensed with, since the invention comprises means whereby a definite position of reference or zero position may be determined by the sense of touch or by the sense of sound, after which the wheel may be set in any of its various positions as related to such zero position, without the aid of visual markings.

As best illustrated in Fig. 7 all but one of the depressions 55 afford cam-like surfaces adapted, on rotation of the permutation wheel in either direction, to lift the head 56 of the detent out of the depression and permit the continued movement of the wheel. One of said depressions, however, is provided with a cam-like surface 57 adapted, on rotation of the wheel in one direction indicated by the arrow in Fig. 7, to lift the head 56 and free the wheel from the detent. Said depression, however, and the head of the detent are provided with cooperating surfaces 58, 59 adapted to be brought into a movement-obstructing relation on movement of the permutation wheel in a direction opposite to that indicated by the arrow and prevent further rotation of the wheel after said surfaces have been brought into a contacting relation. These movement-obstructing surfaces afford means whereby a definite position of reference may be determined without reliance upon visible markings. Any position of the wheel relative to such position of reference may also be determined in like manner because of the resistance to rotation set up between the detent and the wheel whenever the head of the detent enters one of the depressions 55.

In order to facilitate the setting of the lock to be opened in accordance with any desired combination, the markings on the sleeve-shifting heads 50, 50', 50'' may be applied according to some known relationship between the abutments 25 on the sleeves, the slots 26 in the permutation wheels, and the zero positions or positions of reference of said wheels. For example, they may be so related that the abutments and slots will all be in registration, as indicated, in Figs. 1, 2, 3 and 4, when the zero markings on the permutation wheels are centrally positioned

with respect to the slots 23 in the casing and when the zero positions of the sleeve-shifting heads are directed toward the rear face of the lock so as to be exposed in positions adjacent the heads of the detents 35 on removal of the cover-plate 60 (Fig. 3) with the markings applied in the order in which they are indicated in Figs. 2, 4 and 7 of the drawings. If any sleeve-shifting head is shifted to a position such that any other marking takes the place of the zero, as, for example, "7", the permutation wheel will have to be moved to its corresponding position in order to bring its slot in registration with the associated abutment 25. If the peripheries of the permutation wheels are numbered from "0" to "9", this may be effected by rotating the wheel until the number "7" is centrally located with respect to the slot 23 in the casing. If it is desired to set the permutation wheel without reliance upon visible markings, as, for example, when it becomes necessary to operate the lock in the dark, the permutation wheel may be rotated in the direction opposite to that indicated by the arrow in Fig. 7 until it is brought to rest by the detent. This apprises the operator that the wheel has been brought to its zero position. It can then be moved to its "7" position by rotating the wheel in the opposite direction and counting the successive positions "1", "2", "3", etc., through which the wheel is rotated as the head of the detent enters the various depressions 55. This can readily be perceived by the sense of touch or by the sense of sound in view of the clicking noise which will be made as the detent enters each recess.

If desired, means may be provided which will prevent the discovery of the positions of the slots 26 in the inwardly-directed flange-like portions 61 which form the movement-obstructing parts of the permutation wheels, by rotating the knob sufficiently to bring the abutments 25 in contact with said movement-obstructing surfaces, and then rotating the permutation wheel until the slotted portion is brought into registration with said abutments. Such means may comprise a series of recesses 62 spaced in accordance with the different positions in which the permutation wheel may be set, and each having an entrance portion conforming with the entrance portion of the slot 26. These false slots will prevent the detection of the real slot by an attempt to ascertain the combination of the lock in the above-described manner, since the sensation produced by the false slots will be identical with that produced by the real slot and prevent one from being distinguished from the other through the sense of sound or the sense of touch.

The detailed form and construction of parts of the lock will vary materially in accordance with the specific use to which it is

to be applied and the manner in which it is to be assembled and disassembled. In the form herein disclosed, the lock may readily be assembled as follows:—

5 The permutation wheels may first be inserted with their slots 26 in alignment with each other and with the slot 63 in the partition 30.

10 The sleeves 24, 24', 24'' may then be assembled, one within the other, with their abutments 25 in alignment and in registration with the slots in the permutation wheels. These parts may then be introduced through the opening in the left end of the lock as 15 illustrated in Fig. 1, the abutments 25 being passed through the slot 63 in the partition and the slots 26 of the permutation wheels.

15 The spring 47 and detachable attaching element 44 of the operating device may then be inserted from the rear of the casing and the operating device 40 introduced from the left, after which the locking member may be inserted from the right and the parts of the 20 operating member and locking member secured together by the screws 45 and 46, an opening 64 being provided in the casing for the insertion of the screw 46, if desired. The heads 50, 50', 50'' may then be applied 25 to the sleeves 24, 24', 24'', and the heads, sleeves and locking member secured in assembled relation by means of a nut or other suitable fastening element 65.

30 The manipulator 37 may next be inserted 35 from the face of the lock, the detents secured in place from the rear, the cover-plate 60 applied and secured by screws or other suitable fastening devices 66, and the manipulator secured in position by the ring 48 and screw 49.

35 The lock may then be inserted in an opening prepared for the purpose in the door or other object on which it is used, and held in place by appropriate fastening devices, as, 40 for example, the screws 67.

45 The operation of the lock may now be readily described. With the parts in the 50 positions illustrated in Figs. 1, 3 and 4 the mechanism is effective as an ordinary door latch. If the manipulator be rotated in a 55 counterclockwise direction as indicated in Fig. 1, the locking member will be moved to the left to the position indicated in Fig. 2, and the door or other object to which the 60 lock is applied may be opened. On releasing the manipulator the locking member will be restored to the position indicated in Fig. 1, by the spring 47. Should it be desired to render the lock effective, this may 65 be accomplished by rotating one or more of the permutation wheels 22 out of set relation, after which movement of the locking member is prevented by the part 61 of the 70 permutation wheel and the abutment 25 of the associated sleeve. The locking member

may then be released only by restoring the various permutation wheels to "set" position so as to bring the slots 26 and the abutments 25 in alignment.

75 If it is desired to maintain the lock or latch in an ineffective relation, this may be accomplished by rotating the manipulator in a counterclockwise direction until the locking member is moved to the position indicated in Fig. 2, and then moving one or more 80 of the permutation wheels out of their "set" position while retaining the other parts of the mechanism in the positions indicated in Fig. 2. The return of the locking member to the position indicated in Fig. 1 by the 85 spring 47 will then be prevented by the movement-obstructing elements of the permutation mechanism. Yet each of the permutation wheels may be rotated without limit, the movement of the locking member from 90 the position shown in Fig. 1 to the position shown in Fig. 2 being such as to cause each abutment to pass entirely through the slotted portion of the associated permutation wheel and come to rest within the part of 95 the next permutation wheel which affords clearance space providing for its rotation. When it is desired to restore the lock to the condition illustrated in Fig. 1 the permutation wheels need only be returned to "set" 100 position, after which the locking member will be shot to its effective position.

105 When it is desired to change the combination of the lock, the face-plate 60 is removed, (or an opening may be provided 100 therein for such purpose), the retaining member 53 lifted to a position such as to free the sleeve-shifting heads 50, 50', 50'', after which the positions of the abutments 25 may be varied in any desired manner, dependent 110 upon the new combination to be used in the releasing of the lock. The retaining element 53 should then be returned to its holding position and the face-plate reapplied.

115 In order that the locking member and associated elements may freely move to the ineffective position indicated in Fig. 2, with the abutments 25 set for operation in accordance with any desired combination, a cylindrical channel 68 is provided in the partition 30 affording clearanceway for the abutment 120 in any position in which it may be placed.

125 It will be apparent that an important feature of the lock is the provision of the pairs of movement-obstructing elements of which one element has a part preventing movement of the other except when set in a predetermined position. It is a matter of little importance which element of each pair is mounted in the casing and which is mounted on the locking member. The relative positions of the various pairs of elements are also a matter of little importance, although the end-to-end concentric relation herein disclosed results in a relatively compact structure.

ture highly economical of space. It is also of little importance which set of elements is arranged to be shifted only when it is desired to change the combination of the lock 5 and which set is intended to be manipulated at each operation for locking and lock-releasing purposes. All that is essential in this respect is that the parts intended to fix the combination shall be inaccessible when the 10 structure, to which the lock is applied, is locked, and that the other set of elements shall be accessible at such time so that they may be manipulated to set the lock in accordance with the predetermined combination. 15

The invention is not intended to be limited to the specific form herein disclosed for purposes of illustration, but should be regarded as including modifications and variations 20 within the scope of the appended claims.

What I claim is:

1. A combination lock having a locking member and a permutation mechanism to 25 control the movement thereof, said mechanism comprising pairs of cooperative movement-obstructing elements, one of the movement-obstructing elements of each pair having parts so disposed as to lie in the path of lock-controlling movement of a part of the other except when one of the movement-obstructing elements is set in a predetermined position with respect to the other, the movement-obstructing elements which cooperate 35 with the said settable elements being shiftable to various positions relative to each other, whereby the lock may be selectively set for operation in accordance with any one of a number of different combinations.

40 2. A combination lock having a locking member and a permutation mechanism to control the movement thereof, said mechanism comprising pairs of cooperative movement-obstructing elements, one of the movement-obstructing elements of each pair having parts so disposed as to lie in the path of lock-controlling movement of a part of the other except when one of the movement-obstructing elements is set in a predetermined position with respect to the other, the movement-obstructing elements which cooperate 45 with the said settable elements being shiftable to various positions relative to each other and having indicia-bearing heads connected therewith, whereby they may be shifted to selectively condition the lock for operation in accordance with any one of a number of different combinations.

55 3. A combination lock having a locking member and a permutation mechanism to control the movement thereof, said mechanism comprising pairs of cooperative movement-obstructing elements, one of the elements of each pair having parts so disposed 60 as to lie in the path of lock-controlling

movement of a part of the other except when one of the elements is set in a predetermined position with respect to the other, the elements which cooperate with the said settable elements being shiftable to various positions relative to each other and provided with readily releasable means by which they may be retained in any one of a number of positions to which they may be shifted, whereby the lock may be selectively set for operation 70 in accordance with any one of a number of different combinations by releasing said retaining means and moving the said shiftable movement-obstructing elements to appropriate relative positions. 75

4. A combination lock having a locking member and a permutation mechanism to control the movement thereof, said mechanism comprising pairs of cooperative movement-obstructing elements, one of the elements of each pair having parts so disposed as to lie in the path of lock-controlling movement of a part of the other except when one of the elements is set in a predetermined position with respect to the other, the elements which cooperate with the said settable elements being shiftable to various positions relative to each other, indicia-bearing heads each connected with one of said shiftable movement-obstructing elements and serving as means whereby it may be shifted to change the combination of the lock, and a single releasable catch serving as a means whereby said heads may be retained in any of the various relations in accordance with which they may be shifted. 90 95

5. A combination lock having a locking member and a permutation mechanism to control the movement thereof, said mechanism comprising pairs of cooperative movement-obstructing elements, one of the elements of each pair having parts so disposed as to lie in the path of lock-controlling movement of a part of the other except when one of the elements is set in a predetermined position with respect to the other, the settable element of each pair being provided with means whereby certain of its relative positions with respect to the other element of the same pair may be readily perceived, the elements which cooperate with said settable elements being shiftable to various positions relative to each other and having indicia-bearing heads connected therewith whereby they may be shifted to selectively condition the lock for operation in accordance with any one of a number of different combinations, the indicia on the head of each pair of elements being disposed in accordance 105 110 115

with the various positions to which the settable element of the same pair may be moved and being correspondingly related to a definite position of reference of one of said elements with respect to the other. 120 125

6. A combination lock comprising a 130

mounting member, a locking member mounted therein and movable relatively thereto from an effective to an ineffective position, and vice versa, and a permutation mechanism to control the movement of said locking member, said mechanism comprising pairs of cooperative movement-obstructing elements, one of the movement-obstructing elements of each pair having parts so disposed as to lie in the path of movement of a part of the other except when one of the movement-obstructing elements is set in a predetermined position with respect to the other, one of the movement-obstructing elements of each pair being mounted in said mounting member and the other on said locking member, the respective movement-obstructing elements so associated with each of said members being variably settable in different relative positions, whereby the lock may be selectively conditioned for operation in accordance with any one of a number of different combinations by varying the relative positions of the movement-obstructing elements supported by one of said members and may then be set in its locked or its unlocked relation by moving the movement-obstructing elements supported by the other of said members into or out of a set relation conforming with the particular combination selected.

7. A combination lock comprising a mounting member, a locking member mounted therein and movable relatively thereto from an effective to an ineffective position, and vice versa, and a permutation mechanism to control the movement of said locking member, said mechanism comprising pairs of cooperative movement-obstructing elements, one of the elements of each pair having parts so disposed as to lie in the path of movement of a part of the other except when one of the elements is set in a predetermined position with respect to the other, the settable element of each pair being mounted in said mounting member and movable relatively thereto into and out of its set position, and the other element of each pair being mounted on said locking member but shiftable from one position to another with respect thereto, whereby the combination of the lock may be changed by varying the relative positions of the movement-obstructing elements mounted on the locking member.

8. A combination lock comprising a mounting member, a bolt mounted for reciprocation therein, concentric tubular sleeves rotatably mounted upon an extension of said bolt, said sleeves being of different lengths, disposed with the longer of any two innermost so as to leave an end portion of each sleeve exposed, permutation wheels surrounding the exposed end portions of said sleeves, pairs of movement-obstructing elements each pair comprising an element carried by one of said sleeves, the element carried by each permutation wheel being so disposed as to lie in the path of bolt-releasing movement of a part of the paired element carried by one of said sleeves except when set in a predetermined relation, heads connected with said sleeves whereby they may be moved to various relative positions to change the combination of the lock, and releasable means whereby said sleeves may be retained in the various relative positions to which they may be moved.

9. A combination lock comprising a mounting member, a bolt mounted for reciprocation therein, aligned permutation wheels surrounding a part of said bolt, movement-obstructing elements carried by said bolt and said wheels and capable of being set in locking or lock-releasing relation by variably positioning said wheels, an operating bar extending from said bolt in substantial parallelism with the part surrounded by said wheels but externally disposed with respect to the latter, and a manipulator having an operating connection with said bar.

10. A combination lock comprising a mounting member, a bolt mounted for reciprocation therein, aligned permutation wheels surrounding a part of said bolt, movement-obstructing elements carried by said bolt and said wheels and capable of being set in locking or lock-releasing relation by variably positioning said wheels, an operating bar spanning said wheels and connected with the opposite ends of the part surrounded thereby, and a manipulator having an operating connection with said bar.

In witness whereof, I have hereunto signed my name.

MEADE WILDRICK.

CERTIFICATE OF CORRECTION.

Patent No. 1,656,882.

Granted January 17, 1928, to

MEADE WILDRICK.

It is hereby certified that error appears in the printed specification of the above numbered patent requiring correction as follows: Page 5, lines 63, 67 and 68, claim 3, insert the compound word "movement-obstructing"; and that the said Letters Patent should be read with this correction therein that the same may conform to the record of the case in the Patent Office.

Signed and sealed this 14th day of February, A. D. 1928.

Seal.

M. J. Moore,
Acting Commissioner of Patents.
